(57) **CLAIM**

The ornamental design for a toe cap, as shown and described.

DESCRIPTION

FIG. 1 is a perspective view taken from a front, top, left side of a toe cap according to our design;

FIG. 2 is a perspective view taken from a rear, top, left side thereof;

FIG. 3 is a perspective view taken from a rear, top, right side thereof;

FIG. 4 is a left side elevation view thereof;

FIG. 5 is a right side elevation view thereof;

FIG. 6 is a front elevation view thereof; and,

FIG. 7 is a top plan view thereof.

Throughout the Figures, where shown: (i) the dotted lines showing additional structure of the toe cap are for illustrative purposes only and form no part of the claimed design; (ii) the unshaded surfaces form no part of the claimed design; and (iii) the dotted/dashed lines illustrate unclaimed boundaries of surfaces claimed as part of the design.
